UNITED STATES PATENT OFFICE.

WILLIAM P. ANDERSON, OF CINCINNATI, OHIO, ASSIGNOR TO THE FERRO CONCRETE CONSTRUCTION COMPANY, OF CINCINNATI, OHIO, A CORPORATION OF OHIO.

BEAM AND GIRDER.

1,088,676.

Specification of Letters Patent.

Patented Mar. 3, 1914.

Application filed September 28, 1911. Serial No. 651,711.

To all whom it may concern:

Be it known that I, WILLIAM P. ANDERSON, a citizen of the United States of America, and resident of Cincinnati, county of 5 Hamilton, and State of Ohio, have invented certain new and useful improvements in Beams and Girders, of which the following is a specification.

Heretofore in some instances concrete 10 beams and girders have been of a form which is rectangular in cross-section and the joint between the beams and girders was a right angle, and in other instances the beams and girders have been made of a tapering form, the narrower portion of the taper occurring at the bottoms of the beams and girders. In the first form, great difficulty was experienced in removing the forms from the members, after the concrete 15 had become set. The tapering form of beam and girder facilitates the removal of the form work, but it is found that a greater amount of concrete is used in forming these tapering members, and greater difficulty is 20 experienced in making the tapering form work.

The object of my invention is a concrete beam and girder from which a form work 25 may be readily detached, and in which said ease of detachment is secured without increasing the material in said members, or the labor of making the forms.

Referring to the accompanying drawings, in which like parts are indicated by similar 30 reference letters: Figure 1 is a perspective view of a beam, a girder and the connecting joint embodying my invention. Fig. 2 is a perspective view of the parts of the beam and girder forms for molding a beam, girder 35 and joint embodying my invention. Fig. 3 is a perspective view of a portion of the girder form, taken from the opposite side from the view shown in Fig. 2. Fig. 4 is a perspective view of a portion of the beam 40 form.

Referring to the parts: Girder A and beam B are made with vertical sides, and in the corners between the sides of the beam and the adjacent side of the girder, corner 45 blocks D are formed. These corner blocks

are made wedge-shaped, with the narrower part of the taper occurring near the bottom of the beam. The girder A, beam B and blocks D are formed at one time, so that they are monolithic. 55

I have illustrated a form work by which the beam and girder embodying my invention may be molded. In this form work, the sides e of the girder form have tapering openings e', adjacent to the edges of which 60 and upon the exterior whereof, battens e² e³ are secured. The ends f' of the beam forms f are cut at an angle to the vertical equal to the taper in the corner block D, and upon the inclined ends, battens f² f³ are formed, 65 whereby the ends of the boards at the openings e' and the ends f' of the boards of the beam form, together with the battens e² f² e³ f³, form a tapering mold for the corner blocks D. By this construction, the angle 70 between the lower edge of a board and the concrete with which it contacts, is made obtuse, so that in removing the forms, they may be readily lowered away from the concrete. The sides of the forms being vertical, 75 renders their manufacture easier.

The points, at which the tendency of the form work to bind is most apt to occur, are at the corners between the beams and girders. By having corner blocks with a 80 marked inclination in the sides, I overcome this tendency. Of course, it is recognized that a beam and a girder with slightly inclined sides would not depart from the spirit and scope of my invention, providing corner 85 blocks with comparatively decided tapers were used therewith.

What I claim is:

A monolithic structure comprising rectangular girders, rectangular beams joining the 90 girders, and wedge-shaped blocks located at the juncture of the girders and beams, one face of a block tapering toward the vertical face of the beam and the other face of the block tapering toward the face of the girder. 95

WILLIAM P. ANDERSON.
